UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

CAR-COUPLER-POSITIONING DEVICE.

Application filed January 14, 1927. Serial No. 161,100.

This device relates to means for automatically positioning the coupler of a railway car by gravity.

Two railway cars are automatically coupled together by the movement of their respective couplers forcing the tails of the pivoted knuckles behind gravity locks. The couplers are mounted in the cars so as to permit a limited amount of lateral movement. 5 Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against 10 the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed 15 the "coupling range".

It is very often necessary to couple cars on curves and frequently when the radius of the curve is very small, as is common around industrial plants, the couplers of the two cars will be so far out of alignment that they will 20 not automatically couple. Another object of the invention is to automatically bring such couplers within coupling range. The outside rail of a curved track is raised above the inside rail and I provide means whereby the 25 coupler is moved toward the inside of the curve by gravity. This automatic gravity means also returns the coupler to the longitudinal center of the car when the car moves from the curved to the straight part of the 30 track.

In my device the lateral movement between the coupler and the carrier is eliminated, thus 35 reducing friction and consequent wear on the parts. This is quite an item particularly in sandy countries because couplers are costly and the replacement of a coupler means keeping the car out of service.

Coupler positioning devices reduce the 40 number of broken knuckles and guard arms on couplers which members are frequently

bent or broken when the couplers are not within coupling range. Such devices also reduce the number of accidents to trainmen as they are not required to go between the cars and position the coupler preparatory to coupling. 60

A common form of car coupler positioning device comprises a coupler carrier swingably suspended by links from some part of the car so that the objects and advantages mentioned above are obtained and my invention is an improvement upon such devices and consists in providing a shiftable bearing construction to increase the eccentricity of the weight of the coupler (and its associated 65 parts) about its point of support, thus increasing the resultant forces tending to return the coupler to the longitudinal center of the car (or away therefrom when the car is tipped.) I accomplish this result without necessarily increasing the vertical rise of the coupler. This is important because the A. R. A. standard dimensions only permit 70 $\frac{3}{4}$ " vertical rise of the coupler.

In my device the coupler carrier is swingably suspended from any convenient part of the car by a link at each of its ends and is provided with means, such as lugs, to prevent lateral movement of the coupler relative thereto. These links have a pivot which 75 entirely supports the carrier through a predetermined amount of swinging movement of the links and also when the coupler is in its normal central position. At least one of these links has a portion which has un- 80 restricted movement or action during such predetermined movement, but which engages the car part (or carrier if at the lower end) upon any additional swinging movement in one direction, and causes its pivot to move 85 away from its bearing so that the load on this link is shifted entirely to the said portion. The link may be provided with spaced apart portions on the opposite sides of the link so that a similar action takes place when 90 the carrier moves in the opposite direction, or oppositely projecting portions may be used on the separate links to accomplish the same purpose. In practice the "predetermined movement" of the link would permit 95 the carrier and coupler to move laterally during ordinary running motions of the car.

The shiftable bearing construction may be used on one or both ends of one or both links. It may be used to function on one link when 100

the carrier moves in one direction, and upon the other link when the carrier moves in the other direction. Furthermore, the shiftable bearing construction may be arranged 5 with contacting points or lines between the link and car part or between the link and the carrier but a journaled bearing is preferable to provide greater bearing area, at least during the predetermined movement. In a journaled arrangement, the journal may be on the car part and the journal bearing on the link or vice versa, or in fact the link may have a journal and a journal bearing engaging a journal bearing and journal, respectively, on the car part.

The foregoing description forms a part of my co-pending application No. 116,406, filed June 16, 1926, on car coupler positioning device, and the object of this invention is to 20 improve the structure described therein by eliminating any twisting or torsional movement of the coupler by maintaining the coupler carrier in a horizontal position upon its swinging movement in either direction.

25 In the drawings:

Fig. 1 shows a typical application of my device.

Fig. 2 is a side elevation of Fig. 1.

30 Fig. 3 is a perspective view of one of the links.

Fig. 4 is a perspective view of the carrier.

Fig. 5 is a diagram showing the relation of the parts when the coupler and carrier are moved to one side.

35 Fig. 6 shows a modified form wherein the links are inclined in the opposite direction to that shown in Fig. 1.

Fig. 7 shows my invention applied at the upper ends of the links.

40 The coupler 1 rests upon the carrier 2 between the projections 3. The carrier is suspended to the striking casting 4, or any other convenient car part, by swingable links 5 so that when the coupler moves to one 45 side of the car it is returned to its normal position by gravity. In the form illustrated, the upper ends of these links 5 are provided with trunnions 6-6 which engage pockets 7-7 in the striker and the lower 50 ends of the links are provided with similar trunnions 8-8, which engage pockets 9-9 in the carrier, thus forming pivotal connections between the opposite ends of the links and the car part and carrier, respectively.

55 The pivotal connections (6-6) of the links to the car part are spaced further apart than the pivotal connections (8-8) of the links to the carrier 2 which increases the force of gravity tending to return the 60 carrier and the coupler to the normal central position. When the links, however, are thus placed in oblique positions the carrier 2 also assumes an oblique position upon movement sidewise of the car because upon 65 such an action the lower end of one link is

lowered and the lower end of the other link is raised. Such an action puts a torsion or twist on the coupler which affects its relation to the adjacent coupler and also the relation to its attachment to the draft gear.

70

My co-pending application No. 116,406, referred to, covers an improvement on a swingingly suspended carrier wherein the swinging links are provided with spaced apart portions which, upon movement of the carrier, engage portions of the carrier and entirely support it through any swinging movement greater than a predetermined amount, and the object of this invention is to improve such a device by suspending the 75 links obliquely and maintaining the carrier in a horizontal position by varying the distances between the spaced apart portions and the carrier (or other car part).

80

In the form illustrated, the distance 10 between the carrier 2 and the projection 11 is greater than the distance 12 between the carrier 2 and the projection 13, whereby as the coupler moves to the right, as shown in Fig. 5, the projection 13 in the right hand link supports the carrier at 14 and the projection 11 in the left hand link supports the carrier at 19, thus raising the carrier in a horizontal position. Note that the trunnions 8 are free of their pockets 9. Lines 15 and 16 show the difference in the movements of the links. Each link 5 comprises a shank 20 with a pair of oppositely disposed trunnions (6-6 and 8-8) at each end which form the pivotal connections to the car parts and a pair of oppositely disposed projections (11-13) at one end which extend normal to the trunnions. The angular relation 21 of one of the projections (11) to the shank being greater than the angular (22) relation of the other projection (13) to the shank.

90

95 In the modification shown in Fig. 6 the links are positioned with the pivot points 6-6 on the car part closer together than the pivot points 8-8 on the carrier which would require a slight modification on the spaces 10 and 12, otherwise, the action would be the same as described.

100

105 In the modification shown in Fig. 7 the spaced apart portions 17-18 are shown at the upper ends of the links 5 but the relation of the upper ends of the links and the car part 4 would be substantially the same as the relation of the lower end of the links to the carrier, as shown in Fig. 5. My invention may be used at either or both ends of the links.

110

115 I claim:

1. In a car coupler positioning device a 120 carrier swingably suspended to a car part by links with their pivotal connections to the car part spaced further apart than their pivotal connections to the carrier, the lower 125 end of each link provided with oppositely 130

disposed projections which engage portions of the carrier and entirely support the carrier after a predetermined amount of swinging movement of the carrier, the free movement of the projections toward the middle of the carrier being greater than the free movement of the projections toward the ends of the carrier whereby the carrier is maintained in a horizontal position through any swinging movement greater than said predetermined movement.

2. In a car coupler positioning device a carrier element swingably suspended to a car part element by oppositely inclined links, one end of each link provided with oppositely disposed projections which engage portions of the adjacent element and entirely support the carrier after a predetermined amount of swinging movement of the carrier, the normal clearances between the projections and the adjacent elements being different whereby the carrier is maintained in a horizontal position through any swinging movement greater than said predetermined movement.

25 3. In a car coupler positioning device, a

carrier, swingably suspended to a car part by oppositely inclined links having a trunnion at each end which engage the respective car parts through a predetermined movement of the carrier, one end of each link provided with oppositely disposed projections extending normal to said trunnions which engage portions of the adjacent element and entirely support the carrier after such predetermined movement, the angular relation of one of the projections to the body of the link being greater than the angular relation of the other projection to the body of the link.

4. A link for a car coupler positioning device comprising a shank with a pair of oppositely disposed trunnions at each end, and a pair of oppositely disposed projections at one end of the link which extend normal to the trunnions, the angular relation of one of the projections to the shank being greater than the angular relation of the other projection to the shank.

ARTHUR E. SMALL.
